DESIGN FOR A PILLOW SUPPORT FOR A BED OR SIMILAR ARTICLE

Harry E. Edelson, New York, N. Y.

Application February 1, 1939, Serial No. 82,699

Term of patent 7 years

To all whom it may concern:

Be it known that I, Harry E. Edelson, a citizen of the United States, residing in the city, county, and State of New York, have invented a new, original, and ornamental Design for a Pillow Support for a Bed or Similar Article, of which the following is a specification, reference being had to the accompanying drawing, forming part thereof.

The figure is a perspective view of the pillow support for a bed or similar article embodying my new design.

The side of the upright member of the pillow support which is not shown is identically the same as the side which is shown.

I claim:

The ornamental design for a pillow support for a bed or similar article, as shown and described.

HARRY E. EDELSON.
